UNITED STATES PATENT OFFICE

UZ C. PEMBERTON, OF SEFFNER, AND JOSEPH B. JOHNSON, OF TAMPA, FLORIDA

DESIGN FOR AN ARTIFICIAL BAIT

Application filed November 4, 1929. Serial No. 33,336. Term of patent 7 years.

To all whom it may concern:

Be it known that we, Uz C. PEMBERTON and JOSEPH B. JOHNSON, citizens of the United States, residing at Seffner and Tampa, respectively, in the county of Hillsboro and State of Florida, have invented a new, original, and ornamental Design for an Artificial Bait, of which the following is a specification, reference being had to the accompanying drawing, forming part thereof.

Figure 1 is a top plan view of the article showing our new design.

Figure 2 is a side elevation;
Figure 3 is a bottom plan view; and
Figure 4 is a front elevation thereof.

We claim:

The ornamental design for an artificial bait as shown.

In testimony whereof we affix our signatures.

UZ C. PEMBERTON.
JOSEPH B. JOHNSON.
